UNITED STATES PATENT OFFICE.

REUBEN B. BENJAMIN, OF CHICAGO, ILLINOIS, ASSIGNOR TO BENJAMIN ELECTRIC MFG. COMPANY, OF CHICAGO, ILLINOIS, A CORPORATION OF ILLINOIS.

CARBURETER.

1,186,164.

Specification of Letters Patent. Patented June 6, 1916.

Application filed March 12, 1913. Serial No. 753,836.

To all whom it may concern:

Be it known that I, REUBEN B. BENJAMIN, a citizen of the United States, residing at Chicago, in the county of Cook and State 5 of Illinois, have invented new and useful Improvements in Carbureters, of which the following is a full, clear, concise, and exact description, reference being had to the accompanying drawing, forming a part of this 10 specification.

My invention relates to improvements in carbureters for explosive engines and has for one of its objects the provision of a carbureter which will automatically regulate 15 the air and gasoline supply in accordance with the speed at which the engine is run.

Another object of my invention is to provide a carbureter which due to its automatic regulation will dispense with the use of the 20 butterfly valve now in use for controlling or throttling the engine.

Another object of my invention is to provide a carbureter which while automatically controlling the supply of air and gas to the 25 engine will also permit of the predetermining of the fuel supply to the engine, the automatic regulation operating irrespective of the position to which the controlling means is set.

For the purpose of disclosing my invention I have illustrated in the accompanying drawings certain embodiments thereof.

In said drawings, Figure 1 is a transverse sectional view of one form of carbureter embodying my invention; Fig. 2 is a sectional view taken on the line 2—2 of Fig. 1; Fig. 3 is a sectional view taken on the line 3—3 of Fig. 1; Fig. 4 is a sectional view taken on the line 4—4 of Fig. 2; Fig. 5 is a sectional view taken on the line 5—5 of Fig. 1; Fig. 6 is a longitudinal sectional view of a modified form of carbureter embodying my invention; Fig. 7 is a sectional view taken on the line 7—7 of Fig. 6; Fig. 8 is a sectional view taken on the line 8—8 of Fig. 6; Fig. 9 is a detail sectional view taken on the line 9—9 of Fig. 7; and Fig. 10 is a detail view of the modification of the diaphragm illustrated in Fig. 6.

In the carbureter embodying my invention and illustrated in Figs. 1 to 5, inclusive, I provide a gasoline float chamber 1 which is adapted to receive its supply of gasoline through an inlet port 2 communicating with

the gasoline supply tank by a pipe 3 and controlled by a needle valve 4. This needle valve is mounted upon the hub 5 of a three-armed spider 6, the arms of the spider being connected with suitable floats 7 whereby the needle valve is controlled by the height of 60 the gasoline in the float chamber 1. The top of the float chamber is covered by a diaphragm 8 which is secured over the chamber and between the top of the chamber and the upper casting 9 of the carbureter, suitable flanges 10 on the float chamber and 11 on the upper casting being provided to receive securing bolts 12 for bolting these two parts of the carbureter together. The center of the diaphragm 8 is provided with a spray nozzle in the form of a rivet 13 provided with a cone-shaped opening 14 through which the gasoline from the float chamber is adapted to pass into the carbureting throat 15 of the carbureting chamber. This 70 spray nozzle is controlled by a needle valve 16, the lower stem of which provides a guiding stem for the hub 5 of the spider and is adjustable by means of the screw-threaded connection 17 in the bottom of the carbureter 75 chamber.

The throat 15 comprises an opening through a rotatable nut 18 which is located at the bottom of the mixing chamber 20. This nut is screw-threaded into the casting 85 9 and the screw-threads have a large pitch so that a slight rotation of the nut will cause the same to move vertically. The lower end of the nut when at its lowermost position is adapted to touch the top of the diaphragm 90 8, suitable air ports 21, however, being provided to permit the passage beneath the nut of the air even when the nut is in its lowermost position. The air chamber 22 of the carbureter is located around the bottom portion 95 of the nut 18 and is provided with air ports 23 which communicate with the exterior of the casting 9, a suitable screen 24 being arranged over the exterior of these ports to prevent the entrance of dust and 100 articles of foreign matter.

Centrally disposed within the nut 18 is a stop valve 25 which is supported on suitable spider arms 26 extending from the inner walls of the nut 18 and this valve is 105 located immediately above the gasoline spray valve 14 and in a position to vary the size of the opening of this valve as the dia-

phragm 8 is raised. The nut 18 is adapted to be rotated for the purpose of raising and lowering the same by a laterally extending arm 27, which may be connected by a rod 5 or lever 28 with suitable operating means on the steering wheel of an automobile. In addition to the air inlet ports 23 I provide a second air inlet port which is preferably formed by a vertical channel 29 in the nut 18 and a transverse channel 30 in the top 13 of this nut. This vertical channel as the nut is rotated communicates with an opening 31 through which the arm 27 passes and opens more widely the further the nut is rotated 18 to be raised. In order to maintain the atmospheric pressure in the float chamber 1, I provide a suitable vent 31 which communicates through the pipe 32 with the atmosphere.

20 The operation of the device is as follows: With the nut 18 in the position illustrated in Fig. 1, a maximum supply of gasoline and a minimum supply of air is admitted to the mixing chamber 20. It has been found desirable, as the speed of the engine increases to decrease the richness of the mixture, and by the operation of my carburetor this is automatically brought about. As the speed of the engine increases the suction of 30 the pistons in their cylinders will tend to raise the diaphragm 8, thereby moving the valve 14 in closer proximity to the needle point 25 and tending to decrease the amount of gasoline which is drawn through the 35 valve 14. At the same time the amount of air passing into the mixing chamber is also controlled; therefore, the mixture delivered to the engine is less rich. If it is desired to vary the explosive charge delivered to 40 the engine the nut 18 is rotated, which, in turn, will cause the nut to vertically rise, so that the diaphragm will have to be raised a greater distance before the needle 25 will tend to close the valve 14. At the same 45 time the raising of the nut 18 will admit a greater supply of air to the mixing chamber due to the fact that the nut 18 is raised above the diaphragm, and also due to the fact that the port 30 will be slightly opened. 50 It will thus be seen that by the use of my improved carburetor the richness of the mixture delivered to the engine is automatically varied in accordance with the speed of the engine and at the same time the charge may 55 be manually varied without affecting the automatic regulation. As previously stated the nut 18 can be screwed down until its lower end engages the diaphragm 8. The flow of air is then solely through the small 60 ports 21. Further downward movement of the nut will increase the fuel opening without changing the air opening, whereby a rich mixture can be obtained when desired.

The structure illustrated in Figs. 6 to 10 65 shows a means whereby the closure valve

may be adjusted. In this structure I provide a float chamber 1 similar to the float chamber illustrated in Fig. 1. The gasoline inlet, however, is through the valve 31 in the bottom of the float chamber 1, which inlet is protected by a screen 32. The valve 33 for controlling the gasoline inlet opening is arranged upon the lower end of a stem 34 which is secured to a hub 5 similar to the hub of the float illustrated in Fig. 1. The upper end of the stem 34 is guided in a downward extension of a spray nozzle 35 secured in the center of a diaphragm 8, similar in construction and arrangement to the diaphragm 8 in the structure illustrated in Fig. 1. This extension 35 is provided with a plurality of gasoline inlet openings 36 and a vertically extending central opening 37 through which the gasoline is sprayed into the throat 38, which throat communicates with the mixing chamber 39. As in the structure illustrated in Fig. 1, suitable air ports 23 are provided which communicate with the air chamber 22 and the air passes from this chamber into the throat 38 through openings 21 in the vertically movable nut 18, similar in general construction to the vertically movable nut illustrated in Fig. 1. The opening 37 is controlled by a closure member 40, which is similar in function to the closure member 25 shown in the structure illustrated in Fig. 1. This closure member, however, in Fig. 6 takes the form of a needle valve on the end of a stem 41 which extends up through an extension 42 of the nut 18. This extension projects through the top of the casing forming the mixture chamber 39 and has its end squared to receive the squared opening of the arm 43 by which the nut 18 is rotatable. The stem 41 is screw-threaded into the projection 42 and has its top squared as at 44 to receive a wrench or key to permit the rotation of the stem 41 and thereby adjust the valve 40 with respect to the opening 37 to vary the amount of gasoline fed through said opening. If desired, the quantity of air admitted to the mixing chamber may be caused to be more fully varied by enlarging the head of the rivet through which the valve 37 extends, as shown in Fig. 10. The cone-shaped head 45 shown in this figure will tend to slightly cut down the air supply as the diaphragm is raised to cut down the gasoline supply.

Having thus described my invention, what I claim as new and desire to secure by Letters Patent is:

1. In a carburetor, the combination with a mixing chamber, of a fuel chamber, a diaphragm interposed therebetween, a fuel valve having a seat member and a closure member, one of said members being mounted on the diaphragm and adapted to respond to the movement imparted to the diaphragm by

- the variations in pressure on said diaphragm to control the fuel supply, said valve and diaphragm being so constructed that movement of the diaphragm away from the fuel chamber toward the mixing chamber tends to close said valve opening.
2. In a carbureter, the combination with a fuel chamber, of a mixing chamber, a diaphragm closing the fuel chamber having a fuel supply valve therein communicating with the mixing chamber, said diaphragm controlling the opening and closing of the valve in accordance with the variations in pressure in the mixing chamber, said valve and diaphragm being so constructed that movement of the diaphragm away from the fuel chamber toward the mixing chamber tends to close said valve opening.
3. The combination with a mixing chamber, of a fuel chamber, a diaphragm interposed between said chambers, and a valve for controlling the admission of fuel to said mixing chamber, said diaphragm responding to the variation of pressure in the mixing chamber and controlling the opening and closing of said valve, said valve and diaphragm being so constructed that movement of the diaphragm away from the fuel chamber toward the mixing chamber tends to close said valve opening.
4. In a carbureter, the combination with a mixing chamber, of a fuel chamber, a diaphragm interposed between said chambers, a valve for controlling the admission of fuel to said mixing chamber, said diaphragm responding to the variations of pressure in the mixing chamber and controlling the opening and closing of the valve, said valve and diaphragm being so constructed that movement of the diaphragm away from the fuel chamber toward the mixing chamber tends to close said valve opening, and means for manually varying the extent of closing and opening of the valve by the diaphragm.
5. In a carbureter, the combination with a mixing chamber, of a fuel chamber, a diaphragm interposed between said chambers, a valve for controlling the admission of fuel to said mixing chamber, and a valve for controlling the supply of air to the mixing chamber, said diaphragm responding to the variations of pressure in the mixing chamber and controlling the opening and closing of said valves, said valves and diaphragm being so constructed that increased suction in the mixing chamber tends to close said valves.
6. In a carbureter, the combination with a fuel chamber, of a mixing chamber having a throat, a diaphragm interposed between said fuel chamber and mixing chamber, an air inlet formed between the throat of said mixing chamber and the diaphragm, said diaphragm moving in response to variations in pressure in said mixing chamber and controlling the opening and closing of said air inlet, and means for manually varying the distance between the bottom of said throat and the diaphragm.
7. In a carbureter, the combination with a fuel chamber, of a mixing chamber, a diaphragm interposed between said chambers, said diaphragm having an opening therein for the passage of fuel, and a closure member for said opening, said diaphragm responding to variations in pressure in said mixing chamber and adapted to close said passage when moved toward said closure member under the influence of variations in pressure, said diaphragm and closure member being so constructed that increased suction in the mixing chamber tends to close said full passage.
8. In a carbureter, the combination with a fuel chamber, of a mixing chamber, a valve for controlling the admission of fuel from the fuel chamber to the mixing chamber having a movable seat and a stationary closure member, means for moving the seat toward the valve member to close the valve when the speed of the engine rises above a predetermined point, means for varying the distance relation between the closure member and its seat, and means for varying the air supply when the distance relation between the closure member and its seat is varied.
9. In a carbureter, the combination with a fuel chamber, of a mixing chamber, a diaphragm interposed therebetween and having a port leading from the fuel chamber to the mixing chamber, a closure member for said port, said diaphragm being so arranged that when the speed of the engine rises above a predetermined point the increased suction of the engine will move the port toward the closure member to cut down the fuel supply to the engine and thereby prevent the increased rise of the speed of the engine.
10. In a carbureter, the combination with a fuel chamber, of a mixing chamber, a diaphragm interposed between said chambers, said diaphragm having a port and a vertically adjustable, relatively stationary closure member for said port, said diaphragm being so arranged that when the speed of the engine rises above a predetermined point the increased suction of the engine will move said port toward the closure member to close the port and thereby cut down the fuel supply of the engine until the speed of the engine drops back to normal.
11. In a carbureter, the combination with a float chamber, of a mixing chamber, a diaphragm interposed between said chambers having a port therein, a relatively stationary, vertically adjustable closure member for said port, said diaphragm being so arranged that the increased suction of the engine when the speed thereof rises above a predetermined point will tend to move the diaphragm

to close the port thereof, and means whereby the air supply will be varied when said closure member is vertically adjusted.

12. In a carbureter, the combination with a mixing chamber, of a fuel chamber, a flexible diaphragm substantially closing the fuel chamber having a main fuel supply port therein communicating with the mixing chamber and forming a valve seat member, means for supplying fuel to said port, and a valve device coöperating with said valve seat member to control the flow of fuel therethrough, said diaphragm and valve device being so constructed that increased suction in the mixing chamber tends to close the fuel supply.

13. In a carbureter, the combination with a mixing chamber, of a liquid fuel chamber, a flexible diaphragm closing the fuel chamber having a port therein communicating with the mixing chamber and forming a valve seat member, means for supplying fuel to said port, and a valve device coöperating with said port to control the flow of fuel to said port, said diaphragm and valve device being so constructed that increased suction in the mixing chamber tends to close the fuel supply.

14. In a carbureter, the combination with a mixing chamber, of a fuel chamber, a flex-

ible diaphragm substantially closing the fuel chamber having a main fuel supply port therein communicating with the mixing chamber and forming a valve seat member, means for supplying fuel to said port, and a valve device coöperating with said valve seat member to control the flow of fuel therethrough, said diaphragm, valve and valve seat being so constructed that the movement of the diaphragm outwardly from the fuel chamber tends to close the port opening.

15. In a carbureter, a fuel chamber, a mixing chamber, a stiff diaphragm therebetween having a substantially central opening therein for the passage of fuel and forming a valve seat member, a valve member coöperating with said seat member to control the flow of fuel therethrough, and an adjustable sleeve extending into the mixing chamber and engaging the diaphragm to control the flow of air and also to operate the diaphragm to control the fuel flow.

In witness whereof, I have hereunto subscribed my name in the presence of two witnesses.

Washington, D. C."

to close the port thereof, and means whereby the air supply will be varied when said closure member is vertically adjusted.

12. In a carbureter, the combination with a mixing chamber, of a fuel chamber, a flexible diaphragm substantially closing the fuel chamber having a main fuel supply port therein communicating with the mixing chamber and forming a valve seat member, means for supplying fuel to said port, and a valve device coöperating with said valve seat member to control the flow of fuel therethrough, said diaphragm and valve device being so constructed that increased suction in the mixing chamber tends to close the fuel supply.
13. In a carbureter, the combination with a mixing chamber, of a liquid fuel chamber, a flexible diaphragm closing the fuel chamber having a port therein communicating with the mixing chamber and forming a valve seat member, means for supplying fuel to said port, and a valve device coöperating with said port to control the flow of fuel to said port, said diaphragm and valve device being so constructed that increased suction in the mixing chamber tends to close the fuel supply.
14. In a carbureter, the combination with a mixing chamber, of a fuel chamber, a flex-

ible diaphragm substantially closing the fuel chamber having a main fuel supply port therein communicating with the mixing chamber and forming a valve seat member, means for supplying fuel to said port, and a valve device coöperating with said valve seat member to control the flow of fuel therethrough, said diaphragm, valve and valve seat being so constructed that the movement of the diaphragm outwardly from the fuel chamber tends to close the port opening.

15. In a carbureter, a fuel chamber, a mixing chamber, a stiff diaphragm therebetween having a substantially central opening therein for the passage of fuel and forming a valve seat member, a valve member coöperating with said seat member to control the flow of fuel therethrough, and an adjustable sleeve extending into the mixing chamber and engaging the diaphragm to control the flow of air and also to operate the diaphragm to control the fuel flow.

In witness whereof, I have hereunto subscribed my name in the presence of two witnesses.
